M. PELZER,
GAS ATTACHMENT FOR HEATING FURNACES.
APPLICATION FILED MAY 16, 1917.

1,310,926.

Patented July 22, 1919.

UNITED STATES PATENT OFFICE.

MATILDA PELZER, OF NORWOOD, OHIO.

GAS ATTACHMENT FOR HEATING-FURNACES.

1,310,926.

Specification of Letters Patent.

Patented July 22, 1919.

Application filed May 16, 1917. Serial No. 169,076.

To all whom it may concern:

Be it known that I, MATILDA PELZER, a citizen of the United States, and a resident of the city of Norwood, in the county of 5 Hamilton and State of Ohio, have invented certain new and useful Improvements in Gas Attachments for Heating-Furnaces, of which the following is a full, clear, and exact description, reference being made to the 10 accompanying drawings, forming part of this specification.

My invention relates to devices which admit of installation in the usual coal, hot air furnace for residence use, for the use of gas 15 fuel.

Many devices have been tried in the past for this purpose but have not proved a success, either because they involved placing the gas burners in a position where they 20 were exposed to the soot or ashes from the coal fire when not in use, or else they involved the necessity of use with a special type of furnace, or the essential modification of the usual furnace before they could be 25 used.

So far as I am informed, also these devices were not successful in heating the residences, or else were very wasteful of gaseous fuel.

30 One of the essential features of my invention is that my device is designed for placing it in the dome on top of all furnaces from which the hot air pipes radiate. The device can thus be set on top of whatever 35 radiator device there is to enforce circulation of air around the fire pot of the furnace, and will heat the incoming air without any extra air ducts or the like, just at the point where it enters the pipes. Not 40 only this, but the heater will be close to the ceiling, being on top of the furnace and the heat will be subjected to less cooling tendency from the air of the furnace room.

It is also desired that the heater be of 45 dome shape so as to present about an equal heating amount of heating surface opposite the outlet of each pipe, and let air pass all the way around it to form an air jacket against overheating the dome shell of the 50 furnace.

The above features and others to be mentioned I accomplish by that certain construction and arrangement of parts to be hereinafter more specifically pointed out 55 and claimed.

In the drawings,

Figure 1 is a side elevation of a furnace with my device in place.

Fig. 2 is a section taken vertically through the furnace.

Fig. 3 is a section showing the means adopted preferably by me when the dome of the furnace is too low to accommodate the device.

Fig. 4 is a plan view taken from above the 65 furnace.

The furnace 1, having a fire pot 2 and a radiator 3, is intended to represent the usual type of hot air furnace in use for residence heating purposes at the present time. The 70 outer shell 4 of the furnace is cylindrical and at the top of the shell 4 is almost universally placed a dome shell 5 of sheet metal like the shell 4, but in the shape of a truncated cone. In this dome shell or cone, the 75 openings 6 for the hot air pipes 17 are cut, so that the pipes radiate from the dome.

Some furnaces vary in height of dome and accordingly I provide a cylindrical collar portion 18 to be secured on the upper 80 edge of the shell 4 of the furnace, in place of the dome, and then mount the dome on top of the cylindrical collar. This collar serves as a mere insert and as is obvious does not require any essential modification of the furnace.

The usual type of furnace has the radiator 3 which causes the air entering the furnace to circulate around in contact with the escaping gases from the furnace. I prefer 90 that my device be merely set on the top edge of this radiator, and there may have to be some modification of the means for securing the device to the radiator, since mere legs may not be sufficient in some instances due 95 to special shape of radiator. Thus while the following description speaks of but one method of attachment, it should be remembered that the plan will be in installation to examine the radiator and equip the fire 100 casing of the device with proper means of seating or attaching it to the radiator. It may also be attached in the furnace in other ways.

The device has a fire casing comprising a 105 circular dome-shape piece 7 of cast metal of considerable thickness, and a base plate 8 of like metal. Running outwardly from the dome at the front of the device is a rectangular port 9, which is closed off at 110

the outer end by a door 10. Extending into the dome through suitable openings beneath the door are the gas fuel pipes 11.

Preferably the burners are made up of 5 perforated pipes each extending in a semi-circle, to make the burners 12, 12, which extend around the dome in close proximity to the inner surface thereof. The casting has in the top an upwardly extending tube 10 13, with a downwardly depending tube 14. The products of combustion pass from the burners in this preferred arrangement around the inside of the dome and thence down through the middle thereof to the 15 lower end of the tube 14, whence they pass up through the tube, into any suitable pipe 15. The space in the interior of the dome may be filled with fire clay balls or the like to retain heat for a considerable period so 20 as to permit regulation of the heat given off by the furnace.

The door to the casting may be employed to regulate the degree of temperature generated within the dome.

25 For mounting the casting or dome on the radiator 3 there are shown the legs 16 which are designed to rest on the radiator and elevate the base 8 above the top of the radiator so as to permit air to pass up through the 30 radiator around the base of the device.

It can be seen that the principle involved in the dome-shaped fire casing is to bring the outer surface thereof approximately equidistant from all pipe openings. There

is no chance of gas or fumes getting into 35 contact with the air that goes into the pipes, except that which may be due to the air duct taking air from the furnace room and gas escaping from a leaking flue or pipe into the room which is likely to occur in 40 any gas furnace, or coal furnace.

The exact shape of the dome is not insisted upon, nor the shape or nature of the burners, nor are the exact means of securing the device in place on the top of the radiator. 45

Having thus described my invention, what I claim as new and desire to secure by Letters Patent, is:—

The combination with a hot air furnace 50 comprising a solid fuel burning element for heating the air, and a casing for the furnace extending in a dome-shape above said burning element, of a separate supplemental heater mounted above and outside of the 55 solid fuel burning element, and in the dome-shaped portion of the furnace casing, said heater comprising a casing to fit within said dome-shaped portion and having a passageway to the outside of the casing through 60 which the air enters the casing, gas burners in the casing, and an outlet from the casing for the products of combustion, said casing being entirely inclosed inside of the furnace casing, as and for the purpose de- 65 scribed.

MATILDA PELZER.
